UNITED STATES PATENT OFFICE.

WILLIAM E. CRANDALL, OF NEW YORK, N. Y., ASSIGNOR, BY MESNE ASSIGNMENTS, TO CHARLES W. F. DARE, OF BROOKLYN, N. Y.

CHILD'S CARRIAGE.

SPECIFICATION forming part of Reissued Letters Patent No. 10,158, dated July 18, 1882.

Original No. 100,121, dated February 22, 1870; Reissue No. 3,972, dated May 17, 1870; Reissue No. 4,223, dated January 3, 1871.
Application for reissue filed June 20, 1882.

To all whom it may concern:

Be it known that I, WILLIAM E. CRANDALL, of the city, county, and State of New York, have invented a new and useful Improvement 5 in Children's Carriages and Rocking-Horses; and I do hereby declare the following to be a clear and exact description of the nature thereof, sufficient to enable others skilled in the art to which my invention appertains to fully understand and use the same, reference being had to the accompanying drawings, making part of this specification, in which—

Figure 1 is a side view of the device illustrating my invention. Fig. 2 is a central vertical longitudinal section thereof. Fig. 3 is a 15 top or plan view.

Similar letters of reference indicate corresponding parts in the several figures.

My invention consists in providing a child's 20 carriage or rocker with a toy-box, which is connected to the frames in a peculiar manner, and serves to keep the rider in the seat; but it may be readily moved over in order to release him when desired.

The body may be mounted on wheels or rockers, and thus form a carriage or rocking-horse at the pleasure of the child.

In the drawings, A A may represent two frames, which, in the present case, are made 30 in the form of horses, which are arranged parallel to each other, with their feet resting on a base, B, which, if desired, may be in the form of rockers of an ordinary rocking-horse.

The frames are connected together by cross- 35 pieces C, which, with the former, constitute a guarded seat, so that a child can readily ride without danger of being thrown or falling out.

In order to render his position still more secure, there is pivoted to the frames in front of the seat a box, D, which in one position holds 40 the child in the seat, and likewise forms a receptacle for his playthings, and in the other position, which is shown by dotted lines, allows the child to remove himself or be removed 45 from the seat.

The box D is pivoted to the frame by pins a, which connect with the front of said box. When the box is turned over it can rest on a front rest or stop, b.

The base B and frames respectively may be 50 connected together by auxiliary cross rods, bars, or braces, or otherwise, for strengthening purposes, and the child may rest his feet on a foot-board, E, which is secured to the base B.

To the base B there is connected in any suitable manner a series of wheels, F, whose bearings should be so constructed that the wheels may be swung or raised up or down, whereby the whole weight may rest either on the wheels 60 or on the bed.

When it is desired to employ the device as a carriage the wheels are swung or moved downward, and by means of suitable pins, G, or other retaining devices the bed is cleared 65 from the floor, and the carriage can then be drawn forward as an ordinary child's carriage.

When the wheels are raised or removed, then the bed should consist of rockers, so that the child can rock himself, after the manner of a 70 rocking-horse.

Should the arms or shafts of the wheels be immovable fixtures, the bed B may consist of a flat board or strip, and not be in the form of rockers.

It will be perceived that the construction of the body A C not only produces a convenient and safe seat for the child, but that the appearance is presented of two horses, which the child can drive simultaneously without straddling either, and thus be protected from falling off.

Suitable harness may be placed on the horses, and the bridle extend within convenient reach of the child.

It is noticeable that the child can neither fall forward, backward, nor sideward, and I thus produce an attractive, amusing, and safe-riding medium.

Having thus described my invention, what I 90 claim as new, and desire to secure by Letters Patent, is—

1. The box D, pivoted at its front or outer portion to the frames A, in combination with the seat C, substantially as and for the purpose described.

2. The box D, pivoted at its front portion to the frames A, in combination with the seat

C and rest b, substantially as and for the purpose described.

3. The wheels F on rockers B, in combination with body and seat A C, substantially as and for the purpose described.

4. The frame A, seat C, box D, bed B, and wheels F, combined and operating together substantially as described.

5. The frames A, seat C, and foot-board E,

combined with the toy-box D, which is pivoted at its front portion, and with the rest b, all arranged for operation substantially as specified.

WM. E. CRANDALL.
